UNITED STATES PATENT OFFICE.

ALBERT A. YOUNG, OF BOSTON, MASSACHUSETTS, ASSIGNOR OF ONE-HALF
TO DAVID HALE, OF SAME PLACE.

AIR-MATTRESS STAY.

SPECIFICATION forming part of Letters Patent No. 496,030, dated April 25, 1893.

Application filed December 12, 1892. Serial No. 454,936. (No model.)

To all whom it may concern:

Be it known that I, ALBERT A. YOUNG, of Boston, in the county of Suffolk, State of Massachusetts, have invented certain new and useful Improvements in Air Goods, of which the following is a description sufficiently full, clear, and exact to enable any person skilled in the art or science to which said invention appertains to make and use the same, reference being had to the accompanying drawings, forming part of this specification, in which—

Figure 1 is a top plan view of an air-mattress or cushion constructed in accordance with my improvement. Fig. 2 is a sectional view enlarged of a portion of the air-sack showing my improved method of attaching the stays; Fig. 3 a top plan view of the same, the cap being broken away; Fig. 4 a plan view with the cap broken away showing modification; Fig. 5 a sectional view showing use of a single stay; and Fig. 6 a plan view with the caps broken away.

Like letters of reference indicate corresponding parts in the different figures of the drawings.

My invention is designed as an improvement on the device shown in United States Letters Patent, numbered 325,227, dated August 25, 1885, granted to me for an improvement in life saving mattresses, and relates especially to that class of air goods which comprise an inflatable sack and are employed for mattresses, cushions and similar articles, the object being to provide means for staying the walls of the air-sack, whereby a more durable device is produced and the danger of accidental leakage is obviated. In goods of this class as ordinarily constructed the walls, A B, of the air-sack are connected by stays to hold them in position and prevent the sack from becoming distorted under the weight of the user. These stays usually comprise two tapes or cords, b, which are passed through the slots, f, in the walls, A B. The ends, g, of the tape are then spread in opposite directions and laid against the outer or rubber-coated face of the air-sack. These ends are then covered by a circular cap, h, which is vulcanized onto the face of the air-sack securing said ends in position. Constant press-

ure being applied to the sack tending to distort the walls in parts of said sack where the pressure does not come, exerts a strain on the corresponding stays. This causes them to tend to spread where they pass through the slot, f, (as shown in Fig. 5) frequently tearing the walls of the sack at the ends of the slot. Such tearing admits air under the cap, h, forcing said cap outward and detaching it from the rubber-coated face of the sack walls. The constant play of these walls also extends the tear caused by the separation of the stays until such tear frequently extends beyond the cap, h, collapsing the sack and rendering it useless. My improvement overcomes this objection. In carrying it out, after the ends, g, of the stays have been passed through the slots, f, and secured to the gummed face of the wall-sacks I dispose a rectangular sheet, k, of "friction-cloth" over the point of spreading of the stay ends and longitudinally of the slot. This friction-cloth is prepared on both faces with gum-rubber and is exceedingly tough. Transversely of said sheet and longitudinally of the stay ends I attach a second sheet, m, of like material, said sheet overlapping slightly the ends of the stays. Over the whole I secure the cap, h, of rubber-faced cloth. The whole is then vulcanized forming an air-tight connection. As the tendency of the companion stays, b, is to spread, the sheet of friction-cloth, m, securely holds their flattened ends together overcoming this tendency and preventing them from tearing open the slot, f. The sheet, k, may be omitted and a sheet, m², of double T-shape and running longitudinally of the stay-ends, g, may be employed, the heads, p, of said sheet overlapping the sides of the stay and attaching to the gummed-face of the sack-wall. This friction-cloth forms an exceedingly rigid connection between the ends of the stays and being vulcanized also to the cap, h, effectually prevents the separation of said stays and the tearing of the sack-wall.

It will be understood that it is not essential to use two stays, b, as a single stay having its ends split to overlap the sack-walls at opposite sides of the slot may be employed or any form of forked end to the stay may be used without departing from the spirit of my

invention. Such form is shown in Figs. 5 and 6. The stay, b^2 , has its ends split longitudinally and centrally forming flaps, g^2 , which are bent in opposite directions over the gummed-face of the sack-walls. A disk, m^3 , of friction-cloth holds these ends and is surmounted by the cap, h . This form is preferable in some respects to the others as it is much cheaper while equally effective.

10 Having thus explained my invention, what I claim is—

1. In an air-sack a stay connecting the sack walls and passing through slots therein, the ends of said stay being divided and secured 15 to the outer faces of said walls at opposite sides of the slots in combination with a sheet of friction-cloth or similar material connecting the members of said ends and a cap-piece covering said sheet and stay ends, said cap 20 being secured to the sack-walls.

2. In an air-sack of the class described, a stay, connecting and passing through slots in the sack-walls, the ends thereof being secured to the outer face of said walls and respectively 25 at opposite sides of the slot in combination with a sheet of friction-cloth or similar material secured to the ends of said stays whereby they are prevented from spreading, substantially as described.

30 3. In an air-sack the combination with the

sack-walls having the stay-slots, of the double end stay passing through said slots and having its ends spread and secured to the faces of said walls; a sheet of friction-cloth or similar material, vulcanized onto the ends of said stay and a cap, h , covering said stay ends, substantially as described.

4. In an air-sack, the rubber-faced walls, A B, provided with the slots, f , in combination with the stays, b , passing through said slots 40 and having their ends, g , secured to the gummed faces of said walls; a transversely arranged sheet of friction-cloth, k , and the longitudinally arranged sheet of friction-cloth, m vulcanized onto said stay ends and 45 the cap, h , secured to said walls and covering said sheets, all being arranged to operate substantially as described.

5. In an air-sack of the class described, the stays, b , passing through slots in the sack-walls and having their ends, g , secured to the gummed faces thereof in combination with a sheet of friction-cloth or similar material secured to and connecting said stay ends, substantially as and for the purpose set forth.

ALBERT A. YOUNG.
